UNITED STATES PATENT OFFICE

GEORGE F. WHITING, OF BROOKLYN, NEW YORK

HAND TRUCK

Application filed December 14, 1928. Serial No. 326,006.

Special objects of this invention are to provide a practical and convenient truck for handling outboard motors and more particularly of such a nature to enable the mounting and unmounting of such motors by means of the truck.

Other objects and novel features of invention, combinations and relations of parts by which the objects are attained will be 10 clear from the following specification:

The drawings accompanying and forming part of this specification illustrate one practical embodiment of the invention and the method of using the same, but it should be understood that the structure may be modified and changed without departure from 15 the true spirit and broad scope of the invention.

Fig. 1 is a vertical sectional view of the 20 truck as on substantially the line of plane 1—1 of Fig. 2 showing the truck as in use as a stand for supporting an outboard motor; Fig. 2 is a front view of the truck as in the use indicated in Fig. 1; Fig. 3 is a 25 cross-sectional and enlarged detail as taken on substantially the plane of line 3—3, Fig. 2 to show the mounting of one of the adjustable motor supports; Fig. 4 is a broken sectional view of the same parts as on substantially the plane of line 4—4 of Fig. 2; Fig. 5 is an enlarged sectional view of one 30 of the side clamps as on substantially the plane of line 5—5, Fig. 2; Figs. 6 and 7 are side views illustrating the method of using the truck in placing and removing the motor; Fig. 8 is a broken part sectional detail 35 as on the plane of line 8—8 Fig. 6, showing in particular the lower motor support and related parts.

The body of the truck is shown as consisting of a substantially rectangular frame, which may be made up of bent rod or pipe and having parallel side members 10 connected at the top by a handle bar 11 and having inwardly extending lower ends 12

joined rigidly by being pinned or riveted at 13 in sockets 14 in opposite sides of a split saddle or motor support 15. The split or open socket 16 in this support is of a width and depth to receive the skeg 17 and support the propeller shaft enlargement 18 of 50 the outboard motor.

The main frame described is braced in the present disclosure by an inside frame made up of an upper handle bar portion 19 and side rods 20 terminating in inwardly angled braces 21 secured to the lower cross bars 12 or at 22, to the lower motor support, in the same manner as indicated at 13, 14. This inside frame may be suitably secured 55 to the outside frame at different points as by means of a surrounding band clamp 23 at the top and by means of the special clamps shown at the sides.

The upper set of the side clamps are made 60 adjustable in the illustration to serve also as special supports for the cylinders or upper parts of the motor. Thus the top plates 24 of said clamps are indicated as arched at 25 to engage over the spaced rods 26 resting on 65 the frame rods and carrying motor block supporting angle irons 27 at their inner ends and the bottom plates 28 of the clamps are shown arched at 29 in a direction at right angles to the arching of top clamp plates to fit about 70 the spaced side rods 10, 20 of the frame. The two plates of each clamp are indicated as held together by a through bolt 30. The top plate is shown as having narrowed end 75 lugs 31 extending down between the side rods of the same to prevent twisting of this plate and the supporting bracket which it carries and similarly the bottom plate is indicated as having narrowed end lugs 32 entering between the bracket rods 26 to prevent twisting 80 of the bracket structure on the frame. The two plates of each clamp are indicated as held together by a through bolt 30. The top plate is shown as having narrowed end lugs 31 extending down between the side rods of the same to prevent twisting of this plate and the supporting bracket which it carries and similarly the bottom plate is indicated as having narrowed end lugs 32 entering between the bracket rods 26 to prevent twisting 85 of the bracket structure on the frame. The two plates of each clamp are indicated as held together by a through bolt 30. The top plate is shown as having narrowed end lugs 31 extending down between the side rods of the same to prevent twisting of this plate and the supporting bracket which it carries and similarly the bottom plate is indicated as having narrowed end lugs 32 entering between the bracket rods 26 to prevent twisting 90 of the bracket structure on the frame.

inward or outward of the frame to suit the relative positions of the cylinders 33 on different makes of outboard motors.

The lower side clamps are shown as made up of top and bottom plates or members 34, 35 suitably arched to embrace the side rods 10, 20 and held together in adjusted relation by through bolts 36. In addition, the bottom members of these clamps are shown as having bearing sockets 37 for the upper ends of the rearwardly angled props 38. These props as indicated particularly in Fig. 1 are substantially V-shape having the lower forwardly projecting legs 39 formed with downward turned journal extensions 40 lined up with the upper journal portions 41 and secured by counter pins or the like 42 in the sockets 43.

The wheels 44 of the truck are preferably of flat wide tread construction, so as to track well over sand, grass or uneven surfaces. The axle 45 on which these wheels are mounted carries the frame through the medium of forwardly and upwardly offset brackets. These brackets, as possibly best shown in Figs. 2 and 8, consist of complementary angular parts 46, 47 of generally L-shape as viewed from above, having cooperating clamping parts at 48 embracing the axle and secured by bolt 49 and other cooperating clamping elements at 50 at right angles to the first clamping members, embracing the side rods 10 of the frame and secured by bolt 51. The outer or main member 46 of the clamp is shown as having an extension 52 in rear of the axle, carrying the bearing 43 for the hinged prop 38 and also carrying an abutment 53 over which the lower leg 39 of the prop can be forced to hold the prop in the inwardly swung inactive position shown in Fig. 8.

To further brace the parts at the bottom, the lower motor support may be tied up to the axle as by having a rearwardly positioned sleeve extension 54 engaged over the axle and pinned thereto at 55.

The concavity 56, Fig. 1, of the lower, open motor supporting bracket provides a firm seat for the propeller shaft housing 18 of the motor and the cylinder supporting brackets 53 firmly support the motor at the top. To prevent any possibility of the motor tilting forwardly off these supports, the motor may be temporarily fastened to the upper portion of the frame as by means of the chain connection indicated at 57, covered at 58 where it extends about the "bright" parts of the motor and having a hook 59 on the lower end releasably engaging about the muffler 60 and engaged with a hook 61 at the upper end connected with the upper handle bar.

The construction disclosed has the advantages of being relatively light in weight but rigid and strong and of providing a positive, practical, portable support for the motor.

A feature of special importance in this in-

vention is that by supporting the motor as disclosed, the clamp by which the motor is mounted on the boat is left free, so that the motor can be lowered in place and hooked over the stern of the boat, while it is yet supported upon the truck and, possibly of more importance, can be picked up by the truck, while it is yet hot after a run and be lifted clear of the boat.

Figs. 1, 6 and 7 in particular, show how the mounting clamp 62 which is pivotally connected with the motor frame at 63, swings free and clear when the motor is supported on the truck, so that the truck can be backed up and lowered down to drop the clamp over the stern board 64 of the boat while the wheels of the truck are still riding on the wharf, or float or other support 65, after the manner indicated in Fig. 6. Then, after the clamp screw has been tightened on the stern board or transom as in Fig. 7 and the motor is actually supported on the boat, the chain 57, if attached, can be unhooked, the frame lowered to carry the supporting brackets 27 away from the cylinders and the truck be pushed forward to lower the lower end of the motor onto the support 65 and to carry the cylinder supporting brackets upwardly and away from the motor structure, the upper portion of the frame in this operation passing freely up over the motor, it being wider than the motor as shown in Fig. 2. In thus detaching the truck from the motor, after the motor is once supported on the boat, it may be tilted on its fulcrum 63 to take the weight of the lower end of the motor off the truck, enabling the truck to be then wheeled freely away from the motor.

In the reverse procedure, that is, picking the motor up with the truck, the motor is tilted to lift the lower end of the motor up over the supporting surface 65, the truck is backed over the tilted motor and then with a further tilting movement, the lower end of the motor may be raised so as to seat in the lower support 15. In this operation, the truck will be lowered over the head of the motor and be drawn rearwardly until the cylinder rests come under the cylinders to bring about the relation indicated in Fig. 6, whereupon after releasing the motor support clamp, the entire motor structure may be raised by the truck and transported wherever required.

Other advantages result from the truck being wide enough to pass over the motor. For instance, the truck may be removed from either side of the motor, the truck may be used as a work stand for rigidly supporting the motor in a fully exposed condition as in Fig. 1 or may be used to hook the motor over a stationary support and then removed to leave the motor mounted on such stationary support. When the props are swung open in the supporting position shown in Fig. 1, they may be restrained in that relation

by the other side of the abutment 53, Fig. 8, and a shoulder 66 adjacent the lower pivot of the prop. Thus the props may be swung and held in either the folded or outstanding positions. When folded, they are entirely out of the way, do not interfere with the manipulation of the truck or motor as will be clear from the dotted lines in Fig. 2 and when opened or spread, the props make of the truck a substantial stand for supporting the motor in substantially upright relation. The desirability of both longitudinal and lateral adjustment of the cylinder rests 27 will be particularly apparent in Fig. 2, which shows how with a motor having "offset" cylinders, the rests may be set as best suited to hold the differently positioned cylinders. The open bearing or support 15 for the lower end of the motor structure forms a seat or saddle for firmly supporting the motor, and because of its open character receives the skeg to act as a guide and enables the motor to be readily unseated from the truck. While the motor is so cradled that it may be readily removed from the truck, accidental slippage or tilting of the motor out of the truck is positively prevented by the chain connection between the motor and the top of the truck.

What is claimed is:

30 1. A hand truck for transporting and installing outboard motors, comprising a portable frame having a support for the propeller end of an outboard motor and supporting means for the motor end of the outboard motor, said frame being of a width to pass entirely over the motor when the motor and frame are relatively shifted to carry the supporting means out of the motor supporting position, said motor supporting means including cylinder rests projecting inwardly of the frame and the lower support having a seat for the propeller shaft housing open in a direction away from the truck to receive the dependent skeg of the outboard motor.

45 2. A hand truck for transporting and installing outboard motors, comprising a portable frame having a support for the propeller end of an outboard motor and supporting means for the motor end of the outboard motor, said frame being of a width to pass entirely over the motor when the motor and frame are relatively shifted to carry the supporting means out of the motor supporting position, said supporting means including

50 motor supporting brackets laterally and longitudinally adjustable on the frame independently one of the other.

3. An outboard motor transporting and placing truck, comprising a frame mounted on wheels having at the lower end of the frame an open bearing for the lower end portion of an outboard motor and having at the upper portion of the frame inwardly projecting rests for the cylinder structure of the motor, the intermediate portion of the frame

between said rests at the top and said open bearing at the bottom being clear of cross pieces and the frame being of a width to clear the motor structure thereby enabling the truck to lower a motor into supported relation on a boat and to be then freed of the supported motor by a relative longitudinal shifting of the truck and motor. ⁷⁰

4. An outboard motor transporting and placing truck, comprising a frame mounted on wheels having an open bearing for the lower end portion of an outboard motor and having inwardly projecting rests for the cylinder structure of the motor, the intermediate portion of the frame being clear of cross pieces and the frame being of a width to clear the motor structure, thereby enabling the truck to lower a motor into supported relation on a boat and to be then freed of the supported motor by a relative longitudinal shifting of the truck and motor and means for confining the motor on the truck to prevent the relative shifting movement described. ⁷⁵

5. A hand truck for an outboard motor having cylinders, a pivotal mounting clamp, a propeller shaft housing and a skeg, comprising a wheeled frame having a seat for the propeller shaft housing, said seat being open at one end to admit the skeg, cylinder rests on the frame and the frame having an opening therethrough adjacent said rests of greater width than the cylinder structure to thereby support the motor with the mounting clamp in the clear, so that the same may be lowered over the stern of the boat while the motor is yet supported on the truck and whereby the truck and supported motor may then be relatively shifted to pass the truck frame over and free of the motor. ⁹⁰

6. A hand truck for an outboard motor having cylinders, a pivotal mounting clamp, a propeller shaft housing and a skeg, comprising a wheeled frame having a seat for the propeller shaft housing, said seat being open at one end to admit the skeg, cylinder rests on the frame and the frame having an opening therethrough adjacent said rests of greater width than the cylinder structure to thereby support the motor with the mounting clamp in the clear, so that the same may be lowered over the stern of the boat while the motor is yet supported on the truck, whereby the truck and supported motor may then be relatively shifted to pass the truck frame over and free of the motor, and folding prop means for supporting and anchoring the wheeled frame in a substantially upright motor supporting position. ¹⁰⁵

7. A truck for an outboard motor, comprising a wheeled frame having an open seat to receive the propeller shaft housing of an outboard motor and having motor supports for the cylinder structure of the motor, said motor supports having transverse shoulders to position the cylinder structure later- ¹¹⁰

ally in the frame, said frame being open between said open seat and said shoulderer motor supports to expose the supporting structure of the motor by which the same is mounted on the transom of a boat, whereby the truck may be employed to lower the motor into supported relation on a boat or to lift it from the supported position on the boat, said motor supports and seat being disengageable from the motor upon relative shifting of the motor and wheeled frame and by reverse operations being engageable in supporting relation to the motor.

In testimony whereof I affix my signature.
